UNITED STATES PATENT OFFICE

2,132,887

SWIVEL CONNECTER

William A. H. Wells, Edgewood, R. I.

Application May 22, 1937, Serial No. 144,193

6 Claims. (Cl. 24—240)

This invention relates to a connecting device, particularly of the character used on the end of a watch chain or the like for connecting the chain to the ring in the stem of a watch, and is sometimes referred to as a swivel; and has for one of its objects the construction of such a device which will effectively prevent the removal of the spring actuated tongue when the parts are in assembled position.

10 Another object of the invention is the provision of means to prevent the twisting of the tongue about a longitudinal axis through the tongue and thus prevent the wings which extend beneath the end wall of the body of the connector from being so disposed that they may be removed through the opening in the end wall of the connector.

15 Another object of the invention is to form a guide for the directing of the spring which urges the tongue toward one extreme of its position in place.

20 Another advantageous feature of the invention which is incidental to the objects thereof is to prevent shot which may be used for the tubing of the connector from getting into the hollow body of the connector.

25 With these and other objects in view, the invention consists of certain novel features of construction, as will be more fully described, and particularly pointed out in the appended claims.

30 In the accompanying drawing:

Fig. 1 is an elevation of the connector finished;

Fig. 2 is a central sectional view thereof with the tongue in closed position;

Fig. 3 is a view similar to Fig. 2 of the tongue in open position;

Fig. 4 is a sectional view on line 4—4 of Fig. 2;

Fig. 5 is a sectional view on line 5—5 of Fig. 3 showing only the tongue and the fingers and their relationship on the end of the hook;

40 Fig. 6 is a sectional view of the hollow body of the connector;

Fig. 7 is an end view of the body of the connector;

Fig. 8 is a top plan view of the shank and tongue in one stage of their formation;

Fig. 9 is a central sectional view of the structure shown in Fig. 8.

45 In the use of connecting devices of the character here shown, often referred to as swivels, it frequently occurs that the tongue which is spring pressed to closed position becomes twisted permitting removal of the tongue from the opening in the hollow body, and it is known that if the swivel be struck in a certain manner the tongue will often be displaced; and in order to avoid this re-

sult I have provided a pair of fingers on the end of the shank of the hook which extends into the body to effectively prevent the twisting of the tongue and removal thereof, and also these fingers serve the advantageous purpose of providing a guide for the insertion of the spring in place while also preventing fine shot which is used in the tubing of these devices from entering the connector to clog up its operation; and the following is a more detailed description of the present embodiment of this invention, illustrating the preferred means by which these advantageous results may be accomplished:

With reference to the drawing, 10 designates the hollow body of the device which is provided with an end wall 11 having an opening 12 therein of the shape shown in Fig. 7. A stud 13 extends from the body to receive a swivel collar 14 which may rotate thereabout and is held in position by the riveting over or heading 15 of this stud 13. 10 A ring 16 is rockably mounted in a bearing 17 in the swivel collar 14, it being bent into abutting relation with the collar as at 18 at the diametrically opposite portion of this collar. 20

The shank and tongue are first fashioned in a single piece 20, as shown in Figs. 8 and 9. By a suitable striking or pressing operation wings 21 are formed at one end of the bar 20 by providing a suitable cup 22 therein to spread the stock in the desired manner. The other end 23 of the bar 20 is formed bifurcated by providing the slot 24 and I bend the fingers 25 at either side of the slot laterally or at right angles to the bar, as shown in Fig. 9, prior to the bending of the bar 20 into generally the shape of a loop, as illustrated in 25 Figs. 1 and 2.

30 After the bar is bent into the loop shape indicated and forming the opening 26 the wings 21 are inserted through the opening 12 by disposing them longitudinally of this opening and then the 35 loop-shaped bar 20 is rocked through 90° to dispose the wings beneath the end walls 11 of the hollow body and the other end of the bar, comprising the laterally extending fingers 25, are 40 inserted through the opening, and this last inserted portion of the bar is soldered in position as at 27, shown in Figs. 2 and 3.

45 The spring 28, shown in Figs. 2 and 3, is then positioned in the slot 24 between the fingers 25 by 50 inserting the bent portion 29 thereof into the position shown having the one arm 30 in a recess 31 between the fingers with its end adjacent the abutment 32 formed by this recess, while the other end or arm 33 is disposed within the recess 34 55

with its end adjacent the abutment 35 formed by this recess.

The tongue portion 36 is then formed distinct from the hook portion 37 and its shank 38 by severing along the line 39 on an angle, as illustrated in Figs. 1, 2 and 3, so that the end 40 of the tongue 36 will abut the beveled end 41 of the hook so as to come to a complete stop and alignment, which is desired. Rocking of the tongue takes place by reason of the convex arcuate surface 42 of the wing riding within the concave surface 43 of the body portion of the device and is guided by the edges of the opening 12 in the end wall 11 of the body.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A connector comprising a hollow body having an end wall with an opening therein, a rockable tongue extending through said opening and having an end in said body with laterally protruding wings extending beneath the end wall at either side of said opening, and means projecting through said opening with a portion disposed within the body and extending laterally thereof terminating opposite said wings to lie in their path and be engaged thereby upon twisting of the tongue about its longitudinal axis so as to prevent it from being twisted into a position where it may be removed through said opening.

2. A connector comprising a recessed body having an end wall with an opening therein, a rockable tongue extending through said opening and having an end in the recess of said body with laterally protruding recessed wings extending beneath the end wall at either side of said opening, and fingers opposite said wings and secured to said body within the same and extending toward said wings but terminating in close proximity thereto with a part disposed inside the recessed portion of the same to engage said wings upon slight twisting of said tongue about a longitudinal axis into a position where it may be removed through said opening.

3. A connector comprising a hollow body, a hook-shaped member having a shank portion with one end in the body, a tongue having an end in the body with wings on either side, fingers opposite said wings on the end of the shank which is in the body, said fingers having a por-

tion extending toward and in sufficiently close proximity to said wings so as to prevent twisting of said tongue about its longitudinal axis through an angle of 90°, and a spring having a portion disposed between said fingers to urge said tongue to closed position, said spring having its ends disposed externally of the hollow body and engaging said tongue and said shank at generally laterally opposed positions.

4. A connector comprising a hollow body having an end wall with an opening therein, a rockable tongue extending through said opening and having an end in said body with laterally protruding wings extending beneath the end wall at either side of said opening, fingers secured to said body and disposed within the same extending toward and in spaced opposed positions to said wings to prevent sidewise twisting of said tongue about a longitudinal axis into a position where it may be removed through said opening, and a spring positioned between said fingers with an end projecting through said opening and engaging the tongue to urge said tongue to closed position.

5. A connector comprising a hollow body having an end wall with an opening therein, a hook member having a shank portion having one end in said body and extending out through said opening, said end having laterally extending fingers with a recess in said shank between the fingers, a tongue having an end in said body and extending out through said opening and rockable about the edge of said opening upon the side wall of said hollow body only, said tongue end having laterally extending wings to move toward and from the free ends of said fingers as rocking occurs without engaging the same and serving to prevent sidewise twisting of the tongue into a position for removal thereof through said opening, said tongue having a recess therein, and a spring having its ends in interfitting position in the recess of said shank and tongue to urge said tongue toward one extreme of its rockable position.

6. A connector comprising a hollow body having an open end, a tongue having an end portion in the body, a hook member having a shank portion with one end extending into said open end in the body, fingers on the end of the shank portion which is disposed in the body and extending at substantially right angles thereto and toward said tongue to extend across said opening into the body, and a bent spring positioned between and guided by said fingers, the said spring engaging said tongue and said shank respectively to urge said tongue to closed position.
